WALL STRUCTURE

Carl Thomas Carlson, Erie, Pa., assignor to Erie
City Iron Works, Erie, Pa., a corporation of
Pennsylvania

Application December 5, 1931, Serial No. 579,239

6 Claims. (Cl. 122—6)

The present invention is designed to improve wall structures, particularly such structures as are used for furnaces. Such walls have been formed by using spaced parallel water-cooled tubes and facing the wall with blocks secured on the inner faces of the tubes either completely covering the tubes, or partially covering the inner face of the tubes and locking these blocks in place by connected bridge pieces engaging the rear part of the tubes. With such structures as heretofore made, the tubes have been locked by the structure against deflection toward each other, but have not been locked against spreading relatively to each other. Consequently the wall as a whole is weak in this respect. The present invention is designed to lock the adjacent tubes against spreading and consequently strengthen the wall. Features and details of the invention will appear from the specification and claims.

A preferred embodiment of the invention is illustrated in the accompanying drawing as follows:—

Fig. 1 shows a perspective view of the wall partly formed.

Fig. 2 a rear elevation of the wall.

Fig. 3 a section on the line 3—3 in Fig. 2.

Fig. 4 an enlarged section of a pair of tubes on the line 3—3 in Fig. 2.

Fig. 5 an elevation of one of the bridge pieces arranged at the back of the tubes.

Fig. 6 a plan view of the bridge piece.

Fig. 7 a rear view of a facing block.

Fig. 8 a section on the line 8—8 in Fig. 7.

Fig. 9 a top view of a lining block.

1 marks the tubes, these being parallel and vertically arranged as in an ordinary furnace wall and ordinarily being connected up with a circulating system of a water heating means.

40 Lining blocks 2 are arranged along the inner face of the tubes, these blocks having the curved portions 3 engaging the inner portions of the tubes, the blocks ordinarily leaving a portion of the tubes between adjacent lining blocks un-

45 covered, but the forming of the lining blocks in a manner leaving a portion of the tubes uncovered is not universally followed and is not necessary in the present invention.

Bridge pieces 4 engage the rear faces of the tubes and are connected by screws 5 with the lining blocks, the lining blocks having screw threaded sockets 6 for receiving the screws. The bridge pieces have grooves 7, the walls of which engage the inner faces of the tubes. The 55 walls of the groove extend each side of the cen-

ters of the rear faces of the tubes and thus lock the tubes against spreading, or against movement toward each other. The bridge pieces and lining blocks have heretofore prevented the movement of the tubes toward each other, but 60 the locking of the tubes against spreading assures a more rigid wall and more certainly secures the tubes in their proper relation.

In order that the bridge pieces may pass beyond the center of the tubes, it is desirable to 65 have the ends of the bridge pieces bridging one space overlap the ends of the bridge pieces bridging the next adjacent space. One manner of accomplishing this is to form the bridge pieces with forked and single ends. In order to 70 make them of one shape they are preferably formed with a fork 8 at one end and a single end 9 opposite the forked end. In this way the forked ends receive the single extensions of the ends of the next laterally adjacent bridge and 75 thus form the overlap so that each bridge piece may pass beyond the center of the tubes engaged and thus lock the tubes in place.

In order that the bridge pieces may actually draw the tubes toward each other I prefer to 80 extend the walls of the grooves 7 in the form of the cam surfaces 4a, the tendency of which is to draw the tubes together and into close engagement with the surfaces 3 as the screws are set up.

What I claim as new is:—

1. In a wall construction, the combination of wall supports in parallel spaced relation; lining blocks on the inner face of the supports, said blocks extending between the supports and having surface engagement with the supports tending to separate the supports; bridge pieces bridging adjacent supports and interlocking with the faces of the supports remote from the spaces bridged to prevent spreading; and means extending between the supports and connecting the bridge pieces and the blocks. 90

2. In a wall construction, the combination of wall supports in parallel spaced relation; lining blocks on the inner face of the supports, said blocks extending between the supports and having surface engagement with the supports tending to separate the supports; bridge pieces bridging adjacent spaces, said bridge pieces having grooves receiving the rear faces of the supports, the walls of the grooves extending to the faces of the supports remote from the space bridged; and means extending between the supports and connecting the bridge pieces and the blocks. 100

110

3. In a wall structure, the combination of wall supports in parallel spaced relation; lining blocks on the inner face of the supports, said blocks extending between the supports and having surface engagement with the supports tending to separate the supports; bridge pieces bridging adjacent supports, the bridge pieces bridging the space between one pair of supports overlapping the bridge pieces bridging the next adjacent space, said bridge pieces engaging the surfaces of the tubes remote from the space bridged, each piece interlocking with the tubes engaged to prevent the spreading of the tubes; and means extending between the supports and connecting the bridge pieces and the blocks. 8
5. A unit for a wall structure comprising a lining block; and a connected bridge piece having one end extension forked and a single extension on the opposite end. 84
6. In a wall structure, the combination of wall supports in parallel spaced relation; lining blocks on the inner face of the supports holding the supports apart; bridge pieces bridging adjacent supports, the bridge pieces bridging the space between one pair of supports overlapping the bridge pieces bridging the next adjacent space, said bridge pieces having camming surfaces engaging the surfaces of the tubes remote from the space bridged, each piece interlocking with the tubes engaged to prevent the spreading of the tubes; and means extending between the supports and connecting the bridge pieces and the blocks. 90
